GRID LEAD-IN CONSTRUCTION

Application filed November 2, 1927. Serial No. 230,572.

Our invention relates to space-current devices and particularly to devices of that character adapted for short-wave radio service.

One of the objects of our invention is to provide a construction for the in-leading wires to the control electrode or grid of a short-wave radio tube.

Another object of our invention is to provide a means for feeding current uniformly to all parts of the control electrode of a radio tube.

Another object of our invention is to provide a structure which shall distribute, as uniformly as possible, the high-frequency electric and magnetic fields due to currents in the grid circuit of a short-wave radio tube.

A further object of our invention is to provide a method for sealing in the conductors leading to the grid of a radio tube without oxidizing the parts within the tube during such sealing operation.

Other objects of our invention will become apparent through reading the following specification, taken in connection with the accompanying drawing, wherein

Figure 1 is a mid section of a portion of a radio tube embodying our invention and

Fig. 2 is a detail view showing the construction of the in-leading wire at the time it is ready to be sealed into the tube.

In radio tubes, at the frequencies now commonly used in broadcasting, the current in the in-leading wire to the control electrode is usually of small magnitude, since it is merely the charging current for that electrode. However, the magnitude of such a charging current increases with the frequency of the current being employed and, in tubes designed for so-called short-wave service, this charging current becomes of considerable magnitude. This is particularly true in tubes of the larger sizes which are used as transmitters in broadcasting.

As a result of the increase in charging current, a problem arises in the way of providing an in-leading conductor which shall be capable of transmitting such a current to the control electrode. The grid lead structure of tubes that operated satisfactorily on 750 kilocycles became red and white

hot and in danger of breaking at any moment when the tubes were operated at 6000 kilocycles and above. In the case of many tubes, the requirements of electrical insulation make it necessary that the in-leading wire shall pass through the tube wall at some distance from the control electrode itself.

One preferred form of supporting structure for the control electrodes of transmitting tubes consists of a reentrant stem projecting into the tube from one end and consisting of a projection from the press which contains the in-leading wires for the cathode. On such a reentrant stem is mounted a metallic collar which may be clamped thereto and from which the wires supporting the control electrode project. In the case of the very high-frequency currents employed in short-wave work, it is necessary to make provision that the current shall be distributed as uniformly as possible among the four support-stays of the control electrode.

In accordance with our invention, accordingly, we provide that the in-leading wires transmitting current to the control electrode shall connect to the collar at points diametrically opposite to each other.

Referring to the drawing, Fig. 1 is a view partly in section, showing the glass wall portion 1 of a high-power transmitter tube. Part of the wall portion of this tube consists of a metal anode 2, the active portions of the grid 15 and cathode 16 being within the anode. The portion 1 has a reentrant stem 3, on which the collar 4, supporting the grid 15, is clamped. In leading wires 17 pass through a press near the middle of the stem 3 and project into the anode 2 to support the cathode therein. Such a method of construction is well known and needs no extended description.

The lead 6 to conduct current through the tube wall to the grid is preferably sealed through the former at a point near the end of the tube. In accordance with our invention, we provide a pair of conductors 7 of ribbon form which are welded to diametrically opposite points on the collar 4 and curve downward and toward each other so that they may be connected to the lead 6 which is

located near the end of the tube and at a point on the circumference 90° displaced from each of these points of connection to the grid.

5 The double curvature of the ribbon leads make them flexible and yielding to stresses longitudinal therein due to thermal expansion and thereby relieves the lead 6 from stress. We have found that a convenient 10 method for connecting the lead 6 to the ribbons 7 is to weld to the latter a member 9, shown most clearly in Fig. 2, which may be of copper and which is provided with a threaded hole. One convenient way of attaching ribbons 7 to member 9 is to make the latter in the form of a hollow bolt which may be passed through holes in ribbons 7. A nut 11 may then be screwed down binding members 7 and 9 together. The two ribbons on 15 the clamp 4 form a triangular structure that is very rigid in respect to the twisting action of the nut 11 while it is being attached thereto. The connection between the two may 20 then be rendered additionally secure by welding 25 them together.

The containing vessel 1 may be of any suitable vitreous material, but the one which we prefer to use is a glass known to the trade as "G702P" glass. The properties of this 30 glass are such that it will make a vacuum-tight seal with conductors of tungsten or molybdenum. If the in-leading wire 6 is made of molybdenum its end may be readily 35 threaded to engage the threaded portion of the member 9. In case, however, a tungsten in-leading wire is used, difficulty will be 40 found in threading its end.

We have found that a tungsten lead may 45 be provided with a threaded portion by welding thereto a short extension 12 of molybdenum or any other metal which may readily be threaded. An alternative expedient is to plate the end of the tungsten wire heavily 50 with copper and to cut the thread in this copper sleeve.

By whatever method the threaded portion 55 is provided on the in-leading wire, the latter may be sealed into the tube by the following method. The anode 2 is first sealed to the outer glass wall-portion 1. A hole with a 60 raised rim 13 is blown at the desired location in the wall. The stem 3 is then constructed and the cathode filament mounted thereon. The ribbon members 7 are affixed to the 65 threaded member 9 in such position as to form substantially a letter V diverging therefrom. The ends are then flexed toward each other and welded to diametrically opposite points on the collar 4. The resulting 70 structure is then cleansed of any adherent oxides by heating it in a hydrogen atmosphere or by any other well-known method and clamped in position on stem 3.

65 The tungsten in-leading wire 6, having the threaded portion formed thereon, is provid-

ed with a flange or collar 14 of glass of proper diameter and location to seal to the rim 13. This wire is then freed from any oxide produced by the glass blower's fires, by dipping it in sodium nitrite, for example. The 70 stem 3 with the cathode and grid electrodes mounted thereon as already described is sealed into container 1, with the threaded hole in member 9 alined with the hole in the rim 13 of the tube wall. The tungsten lead 6 is then inserted through the latter and screwed firmly into position in the threaded member 9. A seal may then be readily made by the 75 glass blower between the glass collar 14 and the raised rim 13 on the tube wall.

The precise dimensions of the various parts of the structure above described depend, of course, upon the rating of the tube which is being constructed. As a specific example, however, we will state that a power-transmitter tube designed to generate watts at a frequency of 20,000 kilocycles per second has its control electrode supported on a collar 4 which may be of Monel metal 4.5 centimeters 80 in diameter and 3 centimeters long. The flexible ribbons 7 which are welded to this collar 4, consist of molybdenum ribbon 0.025 cms. thick by 0.75 cms. wide and approximately 8 cms. long. Adjacent ends of these 85 ribbons are welded to a molybdenum member 9, shown in detail in Fig. 2, which is 1.1 cms. long by 1.2 cms. in its largest diameter. The two ribbons 7 form the sides of this V and diverge at an angle of 60° degrees. These 90 ribbons substantially follow the curve of a cylindrical surface that would be tangent to the face of the nut 11 and would extend 90° around the stem 3 to intersect with the face of the clamp 4. The particular advantage 95 of this shape is that elongation due to heating by high-frequency currents will increase the radius of curvature without strain on the 100 connection to the lead 6.

The in-leading wire 6 is of tungsten 105 5.5 cms. long by 0.3 cms. in diameter. To one end of this is butt welded a molybdenum wire 12 of the same diameter about 1.3 cms. long. This is threaded to fit a threaded hole in the molybdenum member 9. The details of construction will be readily apparent from 110 Fig. 2.

115 It will thus be seen that we have provided a construction for leading current into the support collar for a control electrode which permits an easy installation in the tube and which provides for a uniform distribution of the current to the control electrode. In accordance with the patent statutes, we have shown and described one embodiment of our invention, but various modifications thereof 120 will be apparent to those skilled in the art without departing from the principles which we have disclosed. We desire, therefore, that the appended claims shall be limited only 125 130

by their express terms and in accordance with the prior art.

We claim as our invention:

1. An electrical-discharge device for high frequency comprising a container enclosing a plurality of electrodes, an electrode assembly having means for support from a part of said container, a conductor having a threaded portion supported from another part of 10 said container and flexible ribbon conductors engaging with said threaded portion and diverging from said conductor to connect it to points spaced apart on said electrode assembly.
- 15 2. An electrical-discharge device for high frequency comprising a container having a reentrant stem and enclosing a plurality of electrodes, one of said electrodes having a collar for supporting it upon said stem, a conductor having a threaded portion sealed through the wall of said container, flexible

ribbon conductors diverging from said conductor and engaging said threaded portion for connecting it to points spaced diametrically opposite on said electrode.

3. An electrical-discharge device for high frequency comprising a container having a reentrant stem, one of said electrodes having a collar for supporting it upon said stem, a tungsten conductor sealed through the wall 70 of said stem, and having an end portion comprising a different metal, a threaded portion upon said end portion and flexible ribbon conductors diverging from said conductor 75 engaging said threaded portion and connecting it to diametrically opposite points on said 80 collar.

In testimony whereof, we have hereunto subscribed our names this 7th day of October, 1927.
